[57] **CLAIM**

The ornamental design for an enclosure for the bed of a pick-up truck, as shown and described.

DESCRIPTION

FIG. 1 is a side isometric view of an enclosure for the bed of a pick-up truck showing my new design it being understood that the broken lines are for illustrative purposes only;

FIG. 2 is a rear elevational view thereof;

FIG. 3 is a top plan view thereof;

FIG. 4 is a front elevational view thereof; and

FIG. 5 is a bottom plan view thereof.

The other side of the enclosure is a mirror image of the side shown in FIG. 1.

FIG. 4

FIG. 5

FIG. 3
